UNITED STATES PATENT OFFICE.

REED J. CLARK, JR., OF YOUNGSTOWN, OHIO.

WASHING MACHINE.

Application filed September 7, 1926. Serial No. 133,857.

This invention relates in general to that type of washing machine set forth in my United States Patents Nos. 1,285,943 and 1,347,617, and particularly to new and useful 5 improvements in the construction of such washing machines.

An object of this invention is to provide a device of the character which embodies a novel feature of construction whereby 10 clothes can be thoroughly and quickly cleansed by mechanical means without injury to even the most delicate fabrics.

Another object of the invention is to provide a washing machine which is extremely 15 quick and thorough in its action and will enable large quantities of soiled fabrics to be washed in a short duration of time, which can be operated easily, and which has no delicate parts which are liable to break 20 or get out of order.

A still further object of the invention is to provide hollow conical shaped means affixed in the interior of a washing machine thereby providing catching and rubbing 25 means for the washing of soiled fabrics.

Another object of the invention is to provide means of separating the gases from the soapy solution during the operation of the washing machine.

Other features and advantages of the improved machine will appear clearly from the detailed description given hereinafter and the accompanying drawings in which the same reference numerals indicate like 30 parts throughout the several views, and wherein,

Figure 1 represents a side view of a washing machine, with the outer casing broken away to more clearly illustrate the construction.

Figure 2 is a horizontal sectional view showing particularly the arrangement of the washing arms.

Figure 3 is a detail vertical sectional view 45 of the venting means on the inside of the inner casing and adjacent construction.

Figure 4 is taken on the line 4—4 of Figure 3.

Figure 5 is a detail side view of one of 50 the washing arms.

Figure 6 is a sectional view of Figure 5. Figure 7 is a detail side view of the perforated cup member.

Figure 8 is an end view of the invention showing a washing wringer affixed thereto. 55

Figure 9 is a detail vertical sectional view of the door of the inner casing.

Figure 10 is a detail vertical sectional view of the door and baffle attachment of the outer casing. 60

Figure 11 is a plan view of Figure 10.

The preferred form of construction as illustrated in the drawings comprises an outer spherical casing 12 having flat sides 13 and 14. This outer casing 12 is rigidly secured 65 to a suitable base 13^a of any desired construction. Extending upwardly from base 13^a are supports 14^a and 15, both of which are provided with bearing surfaces 16 and 17 for the shaftings or trunnions 18 and 70 19 which are integrally formed with substantially U-shaped holding strap 20.

The numerals 21 and 22 designate the two complementary halves of the hollow inner casing of the washing machine, said casing 75 having the general shape of a flattened sphere so that a cross section taken in the vertical direction is circular, while a cross section taken at right angles thereof is substantially elliptical, as indicated in Figure 80 2. The curvature portion of the inner casing is provided with transverse corrugations 22^a which diminish at the flat sides. The halves of the inner casings 21 and 22 overlap each other at their maximum diameter 85 and are surrounded by a band 23 conforming to the contour of the casing. At this overlapping junction the casings 21 and 22 and surrounding band 23 are electrically welded together or by any other desirable 90 process, thereby forming a unit casing 23^a. In the same manner the U-shaped strap 20 is integrally joined on the outer surface of the inner halves of the casings 21 and 22.

These casings 21 and 22 are preferably 95 stamped out of flat sheet metal and by providing the same with said corrugations 22^a the spare metal is utilized in the stamping process.

As shown in Figure 4, I provide the trun- 100

nion 18 with a gear wheel 23 so that the inner casing 23^a may be operated by an electric motor 23^b through chain 23^c (Fig. 8). With the exception of the gear wheel on one of the trunnions, a description of the adjacent construction of one of the trunnions applies equally as well as to the other, since they are identical in construction only being disposed at opposite sides relative to each other on the casing 23^a. The trunnion is provided with suitable ring 24 in order to prevent leakage.

A part of the means for venting the contents of the inner casing 23^a is provided by having the opposite sides of the flat portion of said inner casing 23^a turned inwardly at 25 and in concentric arrangement with the trunnions 18 and 19. The diameter of each of the circles of the turned in portion 25 is greater than the width of the overlying strap 20 in order to allow an opening on the sides of the overlying strap to the interior of the casing 23^a. Concentrically arranged and attached at the flared ends 26 on the opposite inner side of the inner casing 23^a is the housing 27. This housing 27 is provided with a sloping side 28 and perforations 29 on its flat circular surface. Disposed centrally in the housing is a flat circular disk 30 with an opening 30^a in the center of it for the reception of tube 31 connecting with the central portion of 25, thereby permitting a free passage from the interior of casing 23^a to the exterior thereof at this elevation. Both inner casing 23^a and outer casing 12 are each provided with a drain plug 31^a and 32^b for drainage. Referring now particularly to Figure 2, I provide novel means for catching, rubbing and releasing the fabrics to be washed when the machine is in operation by providing the inner casing 23^a with a series of projecting arms 32, 33, 34, 35 and 36, attached by any suitable means at the base to the inner spherical casing. Since these arms are alike in construction a description of one will apply to all of them. The arm may be made of a single sheet of metal or two pieces as may be desirable. The arm as also shown in Figures 5 and 6 is circular in shape, running smaller gradually out from the base to the free end which has a large opening 37 directly in the center of the end, as well as with circular corrugations 38 pressed on the sides thereof. These arms are all set at a slanting angle, 32 and 33 being disposed opposite each other and 34, 35 and 36 set at zig-zag relation with respect to each other.

At the upper portion of the inner casing 23^a a door 39 is hinged thereto to, as well as having a washing arm 40 affixed in the same manner and construction as the other arms, as shown in Figure 9.

At the upper portion of the outer casing 12 another door 41 of greater area than door 39,

is hinged on said outer casing 12, upon which a support 41^b is affixed thereon for holding the door 41 when opened. This door 40 is also provided with perforations 41^a and at the inner side with a baffle plate 42 so as to prevent the outward splashing of washing solutions as illustrated in Figures 10 and 11.

In Figure 8, 43 indicates a conventional wringer that may be used in conjunction with my washing machine operated by a motor 44 in a convenient location as illustrated.

Mode of operation.

In the actuation of the washing machine 80 the inner casing 23^a rotates normally in a counter clockwise direction for washing purposes. Assuming that there is a quantity of soiled fabrics placed in this inner casing 23^a with a soapy solution for cleansing purposes. 85 Upon the initial rotation the fabrics are caught by one of the arms and held for a quarter of a revolution and then begins slipping from said arm due to being in a soaked condition and at the same time causing said fabrics to be rubbed. Likewise as this operation is continued the succeeding arms continue to function in the same manner and thereby quickly accomplishing desired results. 90

In order to separate the gas pressures from the cleansing solution during the rotation of casing 23^a it will be noted that the solution is caught in the housing 27 thereby allowing the gas to pass out of opening 30^a into tube 100 31 and then through the perforated door 41 to the atmosphere. Likewise any overflow of the solution passes through 30^a, 31 and then into the outer casing 12. 105

It is contemplated that numerous structural changes may be made in the machine without departing from the scope of the invention, except as the same may be limited by the appended claims.

What I claim is:—

1. A washing machine comprising an outer casing; an inner flat spherical washing casing mounted to rotate in said outer casing; a plurality of projecting arms affixed on the inner spherical surface of said washing casing, said projecting arms serving as catching, rubbing and releasing elements, said arms being circular in shape running smaller gradually out from the base to the free end said free end having a large opening 110 therein, the outer surfaces of said arms having circular corrugations therein, substantially as described. 115

2. A washing machine comprising an outer casing; an inner flat and transversely corrugated spherical washing casing mounted to rotate in said outer casing, a plurality of projecting arms affixed on the inner spherical surface of said washing casing, said projecting arms all placed at an angle to a verti- 120 125

cal plane, some of which are disposed opposite to each other and others set in zig-zag position in respect to one another, thereby causing said arms to serve as catching, rubbing and releasing elements, said arms being circular in shape running smaller gradually out from the base to the free end, said free

end having a large opening therein, the outer surfaces of said arms having circular corrugations therein, substantially as described. 10

In testimony whereof I have affixed my signature.

REED J. CLARK, JR.
